UNITED STATES PATENT OFFICE

ARTHUR I. RISER, OF CHICAGO, ILLINOIS, ASSIGNOR TO U. S. BOTTLES MACHINERY COMPANY, OF CHICAGO, ILLINOIS, A CORPORATION OF ILLINOIS

CAPPING MACHINE

Application filed April 25, 1928. Serial No. 272,634.

My present invention relates to machines for capping screw-threaded bottles, jars, and the like, automatically and aims to provide an appliance of this kind which will operate satisfactorily and efficiently and which will discharge any of the caps for which the bottle or jar or its equivalent is not provided.

To enable those skilled in this art to have a full understanding of the invention, from both structural and functional standpoints, in the accompanying drawings, forming a part of this specification, I have illustrated a present preferred embodiment of the invention, like reference characters being used throughout the several views to designate the same parts.

In these drawings:

Figure 1 is a vertical, central section through the machine on line 1—1 of Figure 2; Figure 2 is a horizontal section on line 2—2 of Figure 1;

Figure 3 is a diagrammatic view of a portion of the mechanism;

Figure 4 illustrates the electrical contact structure and constitutes a fragmentary section on line 4—4 of Figure 5; and

Figures 5, 6 and 7 show a portion of the appliance in its different positions during the capping operation.

Referring to these several views of the drawings, it will be apparent that the appliance includes an upright revoluble shaft 10 and its stationary extension 11 supported in bearings 12, 13, shaft 10 being revolved by a drive-shaft 14 through bevel-gears 15, 16 and carrying a round support 17 provided with a plurality (8 in the present instance) of semi-circular recesses or pockets 18 each adapted to accommodate a bottle or the like 19 having a threaded neck 21 designed to receive a correspondingly threaded cap 34.

The machine incorporates also a shorter, vertical shaft 22 supported inside of a sleeve 33 by a bearing 23 and rotated from shaft 14, in proper timed relation to the other parts of the mechanism, by a pair of sprocket-wheels 24, 24, a cooperating chain 25, a second shaft 26, and coacting bevel-gears 27, 28.

At its upper end, the constantly-revolving

shaft 22 has eight, radiating arms 29, 29 terminating in suitable curved ends 31 adapted to slide the caps 34 individually in a curved path over the top of a stationary table or ledge 32 mounted on the upper end of sleeve 33, the caps being delivered to the top surface of such table, shelf or support in sequence, right side up, from a chute 35 associated with a suitable source of supply, the arms sweeping the caps along until they are removed by other parts of the machine described hereinafter.

Upright shaft 10 has a spider 39 pinned thereon and rotatable therewith, and having eight pairs of aligned, upright bearings 40, 41, each accommodating a rotating, slidable shaft 42 fitted with and slidable through a pinion 43 located between the spider 39 proper and an upper member 45 which affords the bearing 41.

The eight pinions mesh with a stationary large gear 44 so that as the pinions travel around such gear they are revolved about their own axes.

Each shaft 42 and its hollow extension 54 are supplied with a bearing member 46 mounted on the lower end of a slide 47 arranged to reciprocate on the spider and equipped with an operating roller 48 located between a pair of stationary, cam bars 49 and 51 on supports 52 depending from a spider 53.

Shaft 54, into the upper end of which the lower end of shaft 42 is screwed, as shown in Figure 5, carries a lower head or disc 55 forming one element of an appropriate friction-clutch, having a suitable friction disc 56 between and under face of the part 55 and the top flat surface of a skeleton member 57 having an electro-magnet shell 58 fixed in 90 any approved manner in its lower end.

In order to hold such magnet and its companion parts down in their work, a coiled spring 59 encircles the shaft 54 and presses at its upper end against a ball-bearing 60 below the member 46 and bears at its other end indirectly against the head 55, the descent of the related parts being limited by a collar 142 designed, when the shafts have reached their lowermost limit, to engage a 100

ball-bearing 160 just above the element 46, it being understood that the shaft 54 is slideable in both such anti-friction bearings.

The lower opening 61 of the magnet casting 58 has a ring 62 fixed therein and having a central, flaring mouth with a roughened or corrugated wall, whereby it may securely and firmly grasp the cap during its application to the bottle-neck.

10 The magnet 158 has a slideable core 63 normally pressed down by a spring 64 inserted between a disc 65 engaging the bottom end of shaft 54 and an enlargement 66 on the core, the descent of the latter being limited or restricted by an enlargement 67 adapted to bear on the upper face of ring 62.

20 One end of the wire of magnet 158 is grounded onto its casing or shell at 68 and the other end is electrically connected to a contact-ring 69, mounted on, but insulated from, the magnet shell, and cooperating with a spring contact 71 bearing on its edge and electrically connected at its upper end to a contact-ring 72 on an insulation disc 73 on 25 the top of head 55.

25 A telescopic, spring-extensible contact 74 insulated in any approved manner is mounted on the member 46 and at its upper end it is provided with a leaf contact spring 75 adapted to cooperate with a contact 77 mounted on insulation 76 secured to the under surface of the lower cam bar 49.

The operation of the appliance occurs practically as follows:—

35 Assuming that by hand, or by suitable automatic feeding means, the uncapped bottles are delivered into the compartments of the support 17 and are revolved thereby around the axis of shaft 10 at a uniform uninterrupted speed, and that shaft 22 and its arms 29 are feeding the caps on the table or shelf in the manner stated, and that the spider 39 is also revolving, maintaining the capping-heads in register with the bottles beneath 40 them, such heads rotating constantly about their own axes, when any particular cap during its sliding travel on the support 32 comes into register with the corresponding bottle, which passes beneath the cap table, 45 as shown in Figure 1, the magnet will have been energized by the contact brush 75 having slid onto the contact strip or bar 77 and the corresponding capping-head will have been caused to descend by the cam bars to fit 50 over the cap, as indicated in Figure 3.

55 The core of the magnet attracts and holds the cap, and as the capping-head during its unvarying rotation about the axis of shaft 10 sweeps such cap from its support, the 60 cap is held suspended in the head by reason of the action of the magnet thereon.

65 Shortly thereafter, the revolving capping-head and its cap move down by reason of the action of the cam-bars on the roller of such head and apply the cap to the screw-threaded

neck of the bottle beneath, the spring 59 being somewhat compressed and the core of the magnet receding into the latter, as portrayed in Figure 7, whereby the cap may be forcefully revolved about its own axis by the 70 ring 62 to screw it firmly on the neck.

As soon as the cap is screwed fully home on the neck, so that it cannot turn any more, sufficient resistance to such turning will have been created to cause the friction-clutch 55, 75 56, 57 to slip, thus avoiding an excessive action on the cap.

Then as the parts continue their steady rotation about the axis of shaft 10, the capping-head rises due to the cooperation of the cam-bars and roller and the contact 75 runs off of the end of the stationary contact bar 77.

Of course, there are several bottles undergoing simultaneously different phases of the capping operation, so that the machine not only performs its work efficiently, but it also 85 has a high capacity.

In case any bottle cavity on the rotating support 17 does not receive its bottle, the correlated cap will be held by the magnet in its head until the magnet is deenergized by the contact brush 75 leaving the companion bar 77, whereupon, the cap being no longer held by the magnet will drop out of the head, so that the latter will be ready to receive another 90 cap at the proper moment.

I claim:

1. In a capping-machine, the combination of a stationary table, a revoluble support adapted to receive a plurality of screw-threaded containers, a corresponding number of capping-heads on said support above, in register with, and slideable toward and from said containers, means to revolve said support continuously to carry said containers in sequence beneath, and their corresponding capping-heads above, said table, means to rotate said capping-heads continuously about their own axes, means to slide said capping-heads toward and from their companion containers, means to feed screw-threaded caps onto said table, constantly-acting means to slide said caps on said table individually into register with said capping-heads as the latter pass over said table, an 115 electro-magnet in each of said heads, a yieldable magnetic core in each of said magnets to retain the cap in the corresponding capping-head during its travel after it leaves the table until it descends to the container, means to 120 control the electric circuits of said magnets, and means in each said head to grasp its cap sufficiently firmly to screw it on the corresponding container.

2. In a capping-machine, the combination 125 of a stationary table, a revoluble support adapted to receive a screw-threaded container, a capping-head on said support above, in register with, and slideable toward and from said container, means to revolve said 130

- support to carry said container beneath, and said capping-head above, said table, means to rotate said capping-head about its own axis, means to slide said capping-head toward and from said container, means to feed a screw-threaded cap onto said table, means to slide said cap on said table into register with said capping-head as the latter passes over said table, an electro-magnet in said head, a yieldable magnetic core in said magnet to retain the cap in said capping-head during its travel after it leaves the table until it descends to the container, means to control the electric circuit of said magnet, and means in said head to grasp its cap sufficiently firmly to screw it on the corresponding container. 5
3. In a capping-machine, the combination of a stationary table, a revolute support adapted to receive a screw-threaded container, a capping-head on said support above, in register with, and slidable toward and from said container, means to revolve said support to carry said container beneath, and said capping-head above, said table, means to rotate said capping-head about its own axis, means to slide said capping-head toward and from said container, means to feed a screw-threaded cap onto said table into register with said capping-head as the latter passes over said table, electro-magnetic means in said head to retain the cap therein during its travel after it leaves the table until it descends to the container, means to control the electric circuit of said electro-magnetic means, and means in said head to grasp its cap sufficiently firmly to screw it on the corresponding container. 20
4. In a capping-machine, the combination of a stationary table, a revolute support adapted to receive a screw-threaded container, a capping-head on said support above, in register with, and slidable toward and from said container, means to revolve said support to carry said container beneath, and said capping-head above, said table, means to rotate said capping-head about its axis, means to slide said capping-head toward and from said container, means to feed a screw-threaded cap onto said table in register with said capping-head as the latter passes over said table, means recedable in said capping-head to retain the cap in said capping-head during its travel after it leaves the table until it descends to the container, and means in said head to grasp its cap sufficiently firmly to screw it on the corresponding container, said recedable means automatically retreating in said capping-head during such cap screwing operation. 25
5. In a capping-machine, the combination of a cap-supporting table, a revolute support adapted to receive a screw-threaded container, a capping-head on said support above, in register with, and slidable toward and from said container, means to revolve said support to carry said container beneath, and said capping-head above, said table, means to rotate said capping-head about its own axis, means to slide said capping-head toward and from said container, means to feed a screw-threaded cap on to said table in register with said capping-head as the latter passes over said table, means recedable in said capping-head to retain the cap in said capping-head during its travel after it leaves said cap-support until it descends to the container, and means in said head to grasp its cap sufficiently firmly to screw it on the corresponding container, said recedable means automatically retreating in said capping-head during such cap screwing operation. 30
- In witness whereof I have hereunto set my hand.
- ARTHUR I. RISSER.
